UNITED STATES PATENT OFFICE.

ALEXANDER SCHOPF, OF CAMDEN, NEW JERSEY.

DESIGN FOR A RADIO CABINET.

Application filed May 7, 1923. Serial No. 6,098. Term of patent 14 years.

To all whom it may concern:

Be it known that I, ALEXANDER SCHOPF, a citizen of Hungary, residing at Camden, in the county of Camden, and State of New Jersey, have invented a new, original, and ornamental Design for a Radio Cabinet, of which the following is a specification, reference being had to the accompanying drawing, forming part thereof.

Fig. 1 is a block perspective view of a radio cabinet, showing my new design.

Figs. 2 and 3 are side and plan views, respectively, of the same radio cabinet, showing my new design.

I claim:

The ornamental design for a radio cabinet, as shown.

In testimony whereof I have affixed my signature.

ALEX. SCHOPF.
